(57) **CLAIM**

The ornamental design for a perfume watch, as shown and described.

DESCRIPTION

FIG. 1 is a perspective view of the design of a perfume watch;

FIG. 2 is a front view of the design of a perfume watch;

FIG. 3 is a back view of the design of a perfume watch;

FIG. 4 is a top view of the design of a perfume watch;

FIG. 5 is a bottom view of the design of a perfume watch; and,

FIG. 7 is the other side view of the design of a perfume watch.

The broken line showings of a dial and other small portions of the watch are for illustrative purposes only and form no part of the claimed design.
